UNITED STATES PATENT OFFICE

ALBERT NOVAK, OF NEW YORK, N. Y.

FUR HANGER LOOP

Application filed May 27, 1931. Serial No. 540,424.

This invention relates to means by which a fur neckpiece may be hung up.

An object of the invention is the provision of means, preferably in the form of a loop, by which a fur neckpiece may be hung up, part of said means forming a pintle for the clamping jaws usually associated with a fur neckpiece.

Another object is the provision of means for the purpose mentioned which may be held in a set position by the usual spring employed in clamping jaws.

Other objects will be apparent from a reading of the following specification.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Fig. 1 is a fragmentary side elevation of a fur neckpiece including an animal snout covered with fur, to which snout is attached means for clamping the head end of the fur neckpiece to another part of the same, the clamping means being provided with a loop by which the neckpiece is hung on a hook extending from a wall.

Fig. 2 is a bottom plan view of the clamping jaws and the loop associated therewith by which the fur neckpiece may be hung up.

Fig. 3 is a vertical section taken on line 3—3 of Fig. 2, looking in the direction of the arrows; and

Fig. 4 is a view showing means for attaching a rear leg of the neckpiece to the head end to make a loop of the neckpiece.

Referring to the drawings for a more detailed description thereof, the numerals 7 and 8 indicate a pair of coacting jaws, the former being covered with a fabric 9. The

mentioned jaws are each provided with a pair of inwardly extending ears 10 in accordance with the usual construction. A closed loop 12 by which a fur neckpiece 15, shown in Fig. 1, may be hung up, includes an end portion 16 which passes through the mentioned ears forming a pintle for the jaws. A spring 17 is coiled around the mentioned portion 16 of the loop 12 and includes straight end portions 18, one of which presses outwardly against a backward extension 8a of the jaw 8 and the other of which presses outwardly against a backward extension 7a of the jaw 7 to urge the mentioned jaws into clamping relation. The pressure exerted by the straight end portions 18 against the mentioned extensions, urges the same apart, and therefore urges apart the mentioned ears 10 so that said ears exert a binding action on the pintle-forming section or part 16 of the loop 12, whereby the mentioned loop is frictionally held in a set position or, in other words, is prevented from swinging freely, requiring a slight pressure to move it into a desired position. The fact that the loop is prevented from swinging freely is an advantage, as otherwise it would swing into a position at right angles to the jaws and thereby become noticeable, which condition is not desirable. When the loop is not used to hang up the fur piece it is preferably set in a position substantially parallel to the mentioned jaws. The jaw 8, which is shown in dotted lines in Fig. 1, is attached in any suitable manner to an artificial animal snout which is covered, together with the jaw 8, by fur. The neckpiece 15 is hung up by hanging the loop 12 on a hook 20 screwed into a wall 21.

Fig. 4 shows means for detachably connecting a rear leg 25 of the animal neckpiece to the head end in order to loop the neckpiece, said means comprising a ball 26 attached to a cord or link 27 which is secured to the rear leg 25. The ball is passed through the triangular loop 12 which, as previously stated, is frictionally held so that it will remain in a set position, it being evident that, while the ball is small enough to pass through the lower and wider portion of the triangular

loop, it is too large to pass through the upper portion and the ball therefore serves as means for holding the rear leg to the head end of the neckpiece.

5 What is claimed as new is:

1. In combination, a fur neckpiece, clamping jaws carried thereby and means by which the neckpiece may be hung up, part of said means forming a pintle on which said jaws

10 are pivoted, said means comprising a loop.

2. In combination, a fur neckpiece including an animal snout, clamping jaws carried by said snout and means by which the neckpiece may be hung up, part of said means

15 forming a pintle on which said jaws are pivoted, said means comprising a loop.

3. In combination, a fur neckpiece, clamping jaws carried thereby, means by which the neckpiece may be hung up, part of said means forming a pintle on which said jaws are pivoted and a spring for urging the jaws into

20 clamping relation, the jaws including extensions urged apart by the spring to exert a binding action on the pintle whereby the mentioned means is held in a set position.

25 4. In combination, a fur neckpiece including an animal snout, clamping jaws carried by said snout, means by which the neckpiece may be hung up, part of said means forming

30 a pintle on which said jaws are pivoted, and a spring for urging the jaws into clamping relation, the jaws including extensions urged apart by the spring to exert a binding action on the pintle whereby the mentioned means

35 is held in a set position.

35 5. An animal fur neckpiece including a rear leg, a loop secured to the head portion of the neckpiece, and means for detachably securing the rear leg to the loop, clamping

40 jaws secured to the head end of the neckpiece, part of the mentioned loop forming a pintle for the jaws, extensions on the jaws, a spring urging the extensions apart whereby a binding action is exerted on the pintle

45 to hold the loop in a set position, said means comprising a ball linked to the rear leg.

In testimony whereof I hereby affix my signature.

ALBERT NOVAK.
